Inventor:
S. D. Welton

UNITED STATES PATENT OFFICE.

SAMUEL DAVIS WELTON, OF CRAIGSVILLE, PENNSYLVANIA.

WINDOW SHADE AND CURTAIN HANGER.

1,072,889.

Specification of Letters Patent.

Patented Sept. 9, 1913.

Application filed May 28, 1913. Serial No. 770,479.

To all whom it may concern:

Be it known that I, SAMUEL DAVIS WELTON, a citizen of the United States, residing at Craigsville, in the county of Armstrong and State of Pennsylvania, have invented certain new and useful Improvements in Window Shade and Curtain Hangers, of which the following is a specification.

This invention relates to improvements in
10 hangers, and particularly to that type in
which the curtain and shade hangers are
combined.

An object in view is the adaptation of the hanger for adjustment relative to windows of different sizes, provision being made for the uniform adjustment of the shade supporting elements and the curtain supporting element.

With these and other objects in view as
20 will in part hereinafter become apparent
and in part be stated, the invention com-
prises a curtain and shade hanger, a bracket
having relatively adjustable sustaining
means, and adjustable means coöperating
25 therewith and sustained by the bracket for
receiving the curtain.

The invention comprises certain other novel constructions, combinations, and arrangements of parts as will be hereinafter specified and claimed.

In the accompanying drawings: Figure 1 is a perspective view of a curtain and shade bracket embodying the features of the present invention, and illustrated as applied. 35 Fig. 2 is an enlarged detail longitudinal section through one of the clamping sleeves, fragments only of the bracket rods being seen. Fig. 3 is a transverse vertical section taken on the plane indicated by the line 3—3 of Fig. 2. Fig. 4 is an enlarged detail longitudinal vertical section through the curtain rod parts being seen in elevation. Figs. 40 5 and 6 are transverse vertical sections taken on the planes indicated by lines 5—5 and 45 6—6 of Fig. 4.

Referring to the drawings by numerals 1 indicates the central portion and 2, 2 the end portions of the rod forming the curtain and shade bracket, the central portion 1 being connected to each of the end portions 2 by sleeves 3, 3 which surround lapping parts on the said central and end portions. Each of the sleeves 3 is clamped about the rods 1 and 2 by bolts 4, 4 which are passed through the sleeve and between the rods, said bolts being adapted to be loosened for permitting lon-

gitudinal adjustment of the portions 1 and 2 with respect to each portion and to be again threaded to a tightened condition for effecting clamping of the sleeve about the 60 rods.

Midway of the central portion 1, the rod is preferably bent to form a supporting eye 5 which is adapted to receive a sustaining screw or other supporting device 6 which is threaded into or otherwise engages the window frame. Each of the side portions 2 is loosely engaged by a surrounding sleeve which is provided with a tab 7 adapted to be connected to the window frame for supporting the respective side portion 2 and enabling longitudinal reciprocation thereof. 65 70

Each side 2 is bent adjacent the respective side of the window frame to an outstanding position, each outstanding portion being formed with a bend, loop or depression 8 adapted to receive the respective journal of a curtain roller, as indicated for instance at 9 in dotted lines in Fig. 1. Each end portion 2 at the outer terminus of the respective outstanding portion thereof is again bent to

extend in planes parallel to the planes of the window frame engaging portion and extends thence a distance preferably sufficient for extending substantially across the respective side of the window casing, and the last mentioned portion of the bracket rod is bent back upon itself as indicated at 10 and 11 forming return portions 12 and 13. The portion 13 preferably terminates in a pendant hook 14 and the portion 12 forms a curtain receiving rod which extends throughout the length of the bracket and is disposed at its free end to engage the hook 14. For the purpose of ornamentation each bend 11 is preferably covered by a knob or other finishing device 15, the knob 15 adjacent the hook 14 being preferably formed with a serrated or roughened portion 16 adapted to be engaged by the free end of the curtain rod 12 for being sustained against accidental displacement from the hook 14.

The free end of the rod 12 is formed into a penetrating point for facilitating the application of curtains to the rod. The said free end is preferably, as clearly indicated in Figs. 4 and 5, formed as a sliding member 12' adjustable longitudinally of the rod 12 and adapted to be fixedly connected thereto at any point of adjustment. The adjustment is accomplished by having the tip 12' formed with a longitudinal central

bore adapted to receive the rod 12 and to telescope thereover, a portion of the telescopic part of the tip 12' being slotted longitudinally to form clamping prongs or fingers 17, the free ends of which are threaded for receiving a threaded clamping ring 18 adapted to detachably clamp the tapered tip or sliding member 12' in any given adjusted position along the length of the rod 12.

In operation the bracket is preferably secured to the window frame by means of the eye 5 and tabs 7, the bracket being adjusted relative to the frame before its application thereto. The location of the parts as above set forth is such that the shade roller 9 with its shade is disposed between the cut-standing portions of the bracket while the rod 12 with its tip 12' is of sufficient length for extending approximately throughout the width of the side portions of the window casing so that the curtains sustained by the rod 12 extend beyond and conceal the shade roller. Obviously the bracket may be adjusted for any given window by merely effecting a longitudinal sliding movement of portions 2 relative to the central portion 1 and then clamping the parts in such given position, the tip 12' being correspondingly adjusted.

Having thus described the invention, what is claimed as new is:

1. A fixture comprising a bracket having relatively adjustable portions, said adjustable portions having shade sustaining means, and a curtain rod connected to one of the portions of the bracket and adapted to engage the other, the said rod being adjustable relative to the adjustment of the portions of the bracket.

2. In a fixture, an intermediate portion, end portions adjustable longitudinally of the intermediate portion, clamping sleeves connecting the end portions with the intermediate portion, each end portion having an outstanding projection adapted to sustain a shade, and a longitudinally adjustable curtain rod engaging and adapted to be sustained by said outstanding projections.

3. In a fixture, spaced rods, an intermediate rod having a portion lapping the spaced rods, a sleeve at each end portion of the intermediate rod surrounding the respective end portions and the corresponding adjacent portion of the first mentioned rods,

means for clamping the sleeves about said rod, each of the spaced rods being formed with shade roller sustaining means and curtain rod sustaining means projecting laterally therefrom, and a curtain rod connected with one of the spaced rods and extending to and being adapted to be sustained by the other.

4. A fixture comprising an intermediate rod section, spaced rod sections extending adjacent the end portions of the intermediate rod section, means telescopically connecting the end rod section with the intermediate rod section, each of said end rod sections being formed with curtain roller sustaining means and extending beyond the same, the extension of one of the end rod sections being bent back upon itself and formed into a hook and the other being bent back upon itself and formed into a curtain rod extending to and being adapted to lie within the hook.

5. A fixture comprising a longitudinally adjustable body adapted to be connected with a window frame, said body having outstanding curtain roller sustaining projections and an extension beyond each of said projections disposed parallel to the extended planes of the body portion, and a longitudinally adjustable curtain rod carried by said extensions.

6. In a fixture, a body portion having outstanding extensions and a curtain rod sustained thereby, each extension having shade roller sustaining means between the body portion and curtain rod, the body portion being longitudinally adjustable and the curtain rod having a longitudinally adjustable tip.

7. In a fixture, a body portion having outstanding extensions and a curtain rod sustained thereby, each extension having shade roller sustaining means between the body portion and curtain rod, the body portion being longitudinally adjustable, the curtain rod having a longitudinally adjustable tip, said tip being formed with a longitudinal bore adapted to adjustably receive the main portion of the curtain rod, and means for clamping the tip to the rod.

In testimony whereof I affix my signature in presence of two witnesses:

SAMUEL DAVIS WELTON.
